RELAY

Joseph F. Merkel, Rochester, N. Y., assignor to
General Railway Signal Company, Rochester,
N. Y.

Application December 30, 1930
Serial No. 505,518

4 Claims. (Cl. 175—343)

This invention relates in general to relays, and has more particular reference to a counter-weight for a three-position relay.

In connection with three-position relays, it is desirable to provide means for bringing the moving parts back to a neutral or de-energized position from either one of two energized positions, and without thereby swinging the moving parts beyond the center position.

10 With the above and other considerations in view, it is proposed, in accordance with the present invention, to provide a counter-weight for a three-position relay which is simple and durable, very efficient and positive in its action, and at the same time economical to manufacture.

Further objects, purposes and characteristic features of the present invention will appear as the description proceeds, reference being made to the accompanying drawing which show one form 20 which the invention can assume. The drawing is wholly diagrammatic, and is not intended, in any manner whatsoever, to limit the invention to the particular form shown, but is merely for the purpose of illustration. In the drawing:—

25 Fig. 1 is an end view of a portion of a relay to which the invention can be applied.

Fig. 2 is a side elevation of the relay, showing the counter-weight of the present invention.

Fig. 3 is an end elevation of the invention.

30 Fig. 4 is a view similar to Fig. 3, but showing the parts in a different operative position.

Fig. 5 is an exploded view of the invention.

Referring now to the drawing, there is shown 35 a portion of a relay, such as that in Patent 1,766,665, granted June 24, 1930, to J. F. Merkel.

As shown in Fig. 1, a vane 1 is operated, in the usual manner, to either of two energized positions at either side of the de-energized position in which it is shown in the drawing, to thereby operate, through an eccentric 2, to move a fork 3, carrying rollers 4, and thereby rock a carrier bar 5, carrying contacts 6, for cooperating with fixed contacts 7. The eccentric 2, is on a spindle 8, having pivots 9 for permitting the spindle 8 to rock, and on the spindle 8 is a counter-weight 10 for offsetting the weight of the vane 1.

Carried at one end of the spindle 8, is a cross arm 11, which may be integral with the spindle 8, or rigidly attached thereto, and at each end of the cross arm 11, is a projecting grooved pin 12, with a head 12¹, for receiving in the grooves thereof a yoke 13 of a generally triangular form, the yoke having curved sides 14 and 15 and a straight side 16. On the straight side 16 are inwardly projecting lugs 17 and 18 forming receiving sockets

for the pins 12, when the spindle 8 is in de-energized position. Carried by the yoke 13 is a counter-weight 19, having a downwardly projecting stem or arm 20, loosely fitting into a vertically positioned receiving socket 21, for guiding the 60 stem 20.

The yoke 13 has curved sides 14 and 15 formed on arcs of circles swung respectively from the opposite corners of the triangle, the inner edges of the sides 14 and 15 being spaced out of contact 65 with the stems of pins 12, but having their outer faces positioned to bear against the inner faces of the heads 12¹. This avoids binding and undue friction, and at the same time prevents the yoke 13 from coming off of the pins 12.

On operation of the spindle 8 to one or the other of its operated positions, as shown in Fig. 4, one of the pins 12 moves along one of the arcuate sides of the yoke 13, while the other pin, held in place by a lug 17 or 18, raises the yoke 75 and counter-weight 19 in a substantially vertical direction, whereby to exert a bias on the spindle toward its de-energized position.

The arrangement of parts, as shown and described, permits a single counter-weight, 19, to 80 bias the spindle 8 from each of two operated positions to an intermediate de-energized position and hence perform the same function as generally requires two separate counter-weights in this particular art.

The structure shown and described is simple 85 in form and cheap to manufacture, it is efficient in operation, has a long life, and is very simple to inspect and repair.

The above rather specific description of one 90 form of the present invention is given solely by way of illustration, and is not intended, in any manner whatsoever, in a limiting sense. Obviously the invention can assume many different physical forms, and is susceptible of numerous 95 modifications, and all such forms and modifications are intended to be included in this application.

Having described my invention, I now claim:—

1. In a centering means for relays and the like, 100 in combination with a spindle on a fixed pivot, an arm on the spindle and extending to each side thereof, a projecting pin at each end of the arm, a single centering weight, a triangular frame carrying the weight, one side of the frame resting on the pins and carried thereby, whereby rocking of the spindle in either direction causes the pins to raise the centering weight, an arm on the weight, and means restraining the arm and its 105 weight to substantially rectilinear movement.

110

2. In a centering means for relays and the like, in combination with a pivoted spindle, an arm on the spindle and extending to each side thereof, a projecting pin at each end of the arm, a single centering weight, a triangular frame carrying the weight, one side of the frame resting on the pins and carried thereby, whereby rocking of the spindle causes the pins to raise the centering weight, the triangular frame having its other two sides arcuate in form and positioned to be paralleled by, and bear against the head of, one of said pins, while the other pin is raising the frame, whereby the heads of the pins retain the frame in place. 80
3. In a centering means for relays and the like, in combination with a pivoted spindle, an arm on the spindle and extending transversely to each side thereof, a projecting pin at each end of the arm, a single centering weight, a triangular frame carrying the weight, one side of the frame resting on the pins and carried thereby, whereby rocking of the spindle causes the pins to raise the centering weight, the triangular frame having its other two sides arcuate in form and positioned to be paralleled by, and bear against the head of one of, said pins, while the other pin is raising the frame, whereby the heads of the pins retain the frame in place, inwardly projecting lugs on that side of the frame which rests on the pins forming pin receiving sockets, whereby to hold the side of that pin which is not raising the frame out of contact with that side to which it moves parallel. 85

- JOSEPH F. MERKEL.

the frame, whereby the heads of the pins retain the frame in place, and means on that side of the frame which rests on the pins to form pin receiving sockets, whereby to hold the side of the pin, which is not raising the frame, out of contact with the side which it parallels.

4. In a centering means for relays and the like, in combination with a pivoted spindle, an arm on the spindle and extending transversely to each side thereof, a projecting pin at each end of the arm, a single centering weight, a triangular frame carrying the weight, one side of the frame resting on the pins and carried thereby, whereby rocking of the spindle causes the pins to raise the centering weight, the triangular frame having its other two sides arcuate in form and positioned to be paralleled by, and bear against the head of one of, said pins, while the other pin is raising the frame, whereby the heads of the pins retain the frame in place, inwardly projecting lugs on that side of the frame which rests on the pins forming pin receiving sockets, whereby to hold the side of that pin which is not raising the frame out of contact with that side to which it moves parallel.
